US00D941678S

(12) United States Design Patent (10) Patent No.: US D941,678 S
(45) Date of Patent: * Jan. 25, 2022

(54) PACKAGING

(71) Applicant: Alka Global Ltd, Limmassol (CY)
(72) Inventors: Amir Krenzia, Tel-Aviv (IL); Baruch Naeh, Ramat Hasharon (IL)
() Term: 15 Years

(21) Appl. No.: 35/509,702

(22) Filed: Dec. 24, 2019

(80) Hague Agreement Data

Int. Filing Date: Dec. 24, 2019
Int. Reg. No.: DM/206751
Int. Reg. Date: Dec. 24, 2019
Int. Reg. Pub. Date: Jun. 26, 2020

(30) Foreign Application Priority Data

Jun. 28, 2019 (CH) 2019-00431

(51) LOC (13) Cl. 09-05

(52) U.S. Cl.

USPC D9/707

(58) Field of Classification Search
